COMBINATION DIAPER AND URINAL FOR USE

BY MALE PARALYTICS

James Frank Moxley, 107 Hawthorne St., Beckley, W. Va.

Filed Apr. 2, 1963, Ser. No. 270,096

2 Claims. (Cl. 128—295)

This invention is a combination diaper and urinal for use by male paralytics, especially adapted for paraplegia patients, having residual difficulty in the genito-urinary system and lower bowel. Due to lack of satisfactory prosthesis, control of urinary bowel functions is rendered difficult. After several years of experiments with all known types of diapers and urinals for male paralytics, I have worked out a combination which has been found to be practical, and which by actual use over a period of time, has proven to eliminate many of the drawbacks of combinations heretofore used.

An object of this invention is to provide a combination for the intended purpose, which will eliminate secondary conditions, so distressing to patients who find it necessary to wear diapers and urinals twenty-four hours a day, particularly irritations of the skin, so difficult to heal because of the notoriously poor blood circulation of paralytics.

Other objects of the invention are to provide a combination diaper and urinal entity comprising a body-encircling belt for supporting a relatively light-weight blank or panel made of a suitable, durable fabric of sufficient strength to support the urinal entity in the front, and removable or disposable diaper pads in the back of the blank or panel, when in position on the body of the user; to provide a combination including a diaper panel which will positively hold the diaper pad, in contiguity to the rectum, contact of the diaper or pad with the sides of the buttocks and legs being avoided, to obviate pressure areas found where straps and fasteners of various miscellany are employed to engage the diaper with the body of the user; and to provide a combination of this kind, which may be expeditiously removed from and re-engaged with the body of the user, as an entity, without disengaging fasteners, buttons, pins, etc.

A further object of the invention is to provide a combination diaper and urinal unit in which a receptacle, forming a part of the urinal unit, may be disengaged and replaced without removing the diaper entity from the body.

Prior art: 919,875, Johnson, April 27, 1909; 2,606,558, Kennette, August 12, 1952.

The expired patent to Johnson is a suspensory including a receptacle for the male organ, which receptacle affords means for the introduction and discharge of liquid medicaments for the treatment of diseases, including social diseases. The patent to Kennette shows baby pants with means for detachably securing a diaper to the pants. Neither the patent to Johnson nor the patent to Kennette, or the combination thereof could be utilized by male paralytics, in accordance with the teaching of this invention.

Other objects will be apparent from the following description of the present preferred form of the invention, taken with the annexed drawing, wherein:

FIG. 1 is a front elevational view of a diaper entity and urinal unit constructed in accordance with this invention, illustrating its application;

FIG. 2 is a rear elevational view of the same;

FIG. 3 is a detailed fragmentary front elevational view of the diaper entity and urinal unit, a part of the diaper panel being broken away to disclose to advantage the manner of securing the lower end of a diaper pad to the inner wall of the diaper panel;

FIG. 4 is also a fragmentary view of the diaper entity

2

illustrating the sub panel in open position, with the urinal unit partly removed therefrom to disclose details;

FIG. 5 is an end elevational view of the diaper entity and urinal unit, wherein the sub panel is shown both in full lines and dotted lines, in order to illustrate the position of the sub panel when it is disengaged from the panel of the diaper entity, dotted lines being used to show the diaper pad disengaged from the diaper entity panel;

FIG. 6 is an elevational view of the panel of the diaper entity, showing the manner of mounting the diaper pad on the diaper panel;

FIG. 7 is a vertical sectional view taken on the line 7—7 of FIG. 3, looking in the direction of the arrows;

FIG. 8 is a vertical sectional view taken on the line 8—8 of FIG. 10, looking in the direction of the arrows;

FIG. 9 is a cross sectional view of the urinal receptacle taken on the line 9—9 of FIG. 7, looking in the direction of the arrows;

FIG. 10 is a side elevational view of the urinal unit illustrating the manner of engaging an instrument with the screw threaded end of the receptacle, to facilitate turning the latter inside-out for cleansing, the instrument being shown fragmentarily, with a portion thereof broken away; and

FIG. 11 is a side elevational view of the urinal unit illustrating the position of the receptacle and sheath turned completely inside-out, which is the posture desired for cleaning and/or sterilizing the receptacle, parts of the receptacle being broken away to disclose details.

To illustrate the application of this invention, there is shown in FIGS. 1 and 2 of the drawings, a fragment of a human body, including the waist 20, buttocks 21, and legs 22.

The combination of this invention includes a body-encircling belt 23, which supports a diaper entity 24. The entity embodies a blank or panel 25, one end of which is attached to the front of belt 23, as indicated at 26. The opposite end of the blank or panel is attached to the back of the belt, as shown at 27. The entity 24 further embodies a sub panel 28 and a urinal unit 29. The urinal unit is accessible through an opening 30, formed in the lower fore part of panel 25, as advantageously illustrated in FIG. 7. A diaper pad, such as shown at 31, is adapted for detachable engagement with the inner wall of the panel 25, located, as shown in FIGS. 3, 5 and 7. The pads may be disposable or reusable and of a size to cover a substantial area of the panel, from a point near the locus of engagement of the panel with the back of the belt 23, to a point adjacent the lower end of the opening 30, as also shown to advantage in FIGS. 3, 5 and 7. Any suitable means may be used for securing the pad to the panel, such as the stud and socket fasteners shown in the drawings. In this way the pad is held in the desired proximity to the rectum, without undue tightness or binding on the flesh of the user. The sub panel 28, in the form of invention here shown, has one margin sewn or otherwise secured to the panel 25, at point 32, just below access opening 30. The inner side of sub panel 28 is equipped

with studs 33 along its upper margin and along a part of each side of the panel. The studs 33 complement, and are adapted for engagement with sockets 34, secured to the panel 25 as shown in FIGS. 3 and 4. An opening 35 is formed centrally in the sub panel 28 for registry with the access opening 30 of the panel 25, when the sub panel

is in a closed position, as shown in FIGS. 5 and 7. A ring 36 is secured to the sub panel around the opening 35, the exposed face of the ring having sockets 37 mounted thereon.

The urinal unit 29 of the diaper assembly, as shown to advantage in FIGS. 4 and 7, comprises an annular assembly, generally designated 38, embodying a clamping ring

39, washer 40, padded base 41 and receptacle laminae 42. The laminae 42 covers the inner face of the base 41, stretches over the outer periphery of said base and washer, the free ends of the laminae being contiguous to and engaged with the outer periphery of the clamping ring and a portion of the washer, which protrudes beyond said ring. Studs 43 project from the front face of ring 39. The receptacle portion of the urinal receptacle, designated 44, is made of layers of soft, flexible rubber or the like, and has concentrically mounted in its inner end, a tapering truncated cone-shaped sheath 44', through which the male organ extends. The inner end of the sheath overlaps the inner ends of the receptacle layers, and forms a part of the laminae 42 which encases the base 41, washer 40 and clamping ring 39. The studs 43 complement, and are adapted for engagement in the sockets 37 of the sub panel ring 36, when the sub panel is in a closed position, as shown in FIG. 7. The free end of the receptacle 44 is adapted for the reception of a screw-threaded nipple 45. The nipple serves the dual purpose of supporting a closure 46, when the urinal unit is in use, as a connector for an actuator element, for a purpose to be presently described.

In use of the combination herein shown and described, when a diaper pad is secured in position on the panel 25, and urinal unit is in place, as shown in FIG. 5, the entire combination may be slipped up the legs of the user, to a point where the belt 23 encircles the waist and the diaper pad and urinal unit are in appropriate position. The urinal receptacle may be emptied by removing the cap or closure 46, without disturbing the diaper entity. When a pad 31 is to be replaced, the entity is slipped down the legs, to a point where the pad is readily accessible, and there the soiled pad is removed and replaced with a clean one.

It is essential that the interior of the urinal receptacle be periodically cleaned and sterilized. This is greatly facilitated with the present invention by use of a suitable instrument with a screw-threaded bore or socket, threaded on the nipple 45 as shown in FIGS. 10 and 11. Here the instrument is shown to be a rod 47 provided with a screw-threaded recess or socket 48, which complements the screw-threads of the nipple. After urinal unit 29 is removed, by following the modus operandi shown in FIG. 4, where the "up" arrow is designated "U," and the "down" arrow is designated "D," the rod 47 is first engaged with nipple 45, and the rod then pushed in the direction of the ring 39. This continues until the receptacle 44, including sheath 44' have been turned inside-out. The receptacle may then be conveniently cleaned and sterilized in an ob-

vious manner. This is followed by retraction of the rod, which returns the receptacle 44, including the sheath 44', to its normal operating position. By providing the tapering sheath 44' assembled as shown in FIG. 7, backwash of the urine, from the receptacle 44, through the panel 25, is prevented.

While I have herein described the preferred embodiment of my invention, it is nevertheless to be understood that various changes may be made therein, without departing from the spirit and scope of the claims hereto appended.

What is claimed is:

1. A combination diaper and urinal, for use by male paralytics, including a body-encircling belt engageable around the waist of the user, a diaper entity including a panel, the ends of which are secured to the belt, the intermediate part of the panel engaging the crotch of the user, the entity also including a removable pad secured to the panel, in position to span the interstice between the buttocks, said entity further including a urinal unit, accessible through an opening in the front of the panel, the unit embodying a sub panel, the lower margin of which is anchored to the main panel, in close proximity to the bottom of said access opening, the center of the sub panel having an opening adapted to register with the access opening when the urinal unit is in use, a reinforcing ring with stud sockets, secured to the sub panel, around the opening in the latter, the urinal unit also including an apertured ring assembly embodying a flexible bag-like receptacle, with a concentric sheath to embrace the male organ, studs carried by the second-mentioned ring complementing the sockets of the sub panel ring, to permit independent removal of the second-mentioned ring and receptacle.

2. The combination of claim 1 with the addition of studs secured at intervals, to the inner face of the sub panel, and sockets carried by the diaper panel, above the top and at the sides of the urinal access opening, complementing the studs of the sub panel, for detachably engaging the top and sides of the sub panel with the diaper panel.
